COLD PERMANENT WAVING APPARATUS

Victor Leon, New York, N. Y.

Application August 3, 1940, Serial No. 350,760

14 Claims. (Cl. 132—36)

My invention relates to the art of waving the hair upon the head of a person in a manner known as "permanent waving." The methods of waving in most common use depend upon the application of heat, generally by electrically heated units, to the hair while wound on curlers or spindles. The application of heat, however, is attended by serious hazards such as scalp burns, electric shocks and burning of the hair; and there is always considerable discomfort caused by the heating of the head. To avoid these hazards and discomfort there has been proposed a method of "cold waving" which depends upon the setting of the hair by chemical means; in brief this involves the application to the curled strands of a softening agent, for which purpose a solution of ammonium hydrogen sulfide has been used, to set the hair, and then rinsing to remove the agent. Serious complications have arisen from this method of treatment as practiced, since the solution is in direct contact with the scalp and skin infections and at times poisoning have followed from the direct contact.

The present invention provides for a cold wave procedure which eliminates the foregoing complications by an applicator, enclosing a strand of hair wound upon a mandrel or spindle, that can be made fluid-tight to maintain the treating solution out of direct contact with the scalp. The applicator is in the form of a container for housing the mandrel and has a tube opening into it for the entry of a treating solution; the tube is preferably connected to a hollow mandrel within the container which mandrel is perforated to insure flow of the treating solution through the strand of hair wound upon it.

The invention further provides for a uniform and assured application of a treating solution to all strands of hair to be separately curled by enclosing each curler in a separate applicator and applying a pressure equally and continuously on streams of treating solution fed to the individual applicators. In this manner the separate curls are treated alike, and there is thus minimized the tendency to unevenness in the general effect and the failure to sufficiently curl some strands as frequently occurs in the practice of applying a solution directly to the entire scalp; by means of individual applicators it is moreover possible to recurl individual strands which do not satisfy the customer or to curl only selected portions of the hair. The continuously and equally applied pressure is secured by means of a rotary pump which is connected to the tubes; a preferred arrangement for promoting equalized distribution

of liquid to the individual applicators is branch tubes connected to the pump and each of these subdivided in sub-branch tubes connected to the applicators.

Further objects will be seen as the description of my invention proceeds.

In further description of my invention reference is had to the drawings in which—

Fig. 1 is a rear elevation of a lady's head illustrating the invention in assembled form.

Fig. 2 is an enlarged detail on the line 2—2 of Fig. 1, said figure showing a top view of a container that houses the wound hair to be waved and into which the chemical or other fluid liquid is contained.

Fig. 3 is a detail view similar to Fig. 2 showing the container in open position.

Fig. 4 is a front elevation showing the hair to be waved in curled up position, and in readiness to be impregnated with the liquids.

Fig. 5 is a vertical section taken on the line 5—5 of Fig. 1.

Fig. 6 is a detail of a rubber closure member showing said member applied to a lady's head with a strand of hair projecting through a slot in said member, said hair being in readiness for winding around the mandrel or spindle.

Fig. 7 shows an exposed plan view of a modified form of container with the hair curled around a mandrel in said container preparatory to the application of the liquid therein.

Fig. 8 is a transverse section taken on the line 8—8 of Fig. 7.

Fig. 9 is a detail view of a form of mandrel or spindle.

Fig. 10 is a section taken on a line 10—10 of Fig. 9.

Fig. 11 is a perspective view of the rubber closure member.

Fig. 12 is a further modification of the mandrel and liquid container.

Fig. 13 is a view of said container on a line 13—13 of Fig. 12.

Fig. 14 is a section taken on the line 14—14 of Fig. 12 with the rubber closure omitted.

Referring to Fig. 1 said figure shows the manner of distribution and mounting of the container units, upon the head of the person whose hair is to receive a permanent wave. The numeral 20 designates the container units in which the hair in coiled form is contained. 21 are individual sub-branch tubes which are insertible into said container. 22 are tube jointures from which said sub-branch tubes project. 23, 24 and 25 are main branch tubes which terminate into a jointure

member 26, said jointure member is connected to the discharge opening of the pump 27. Said pump may be operated optionally by hand or by some power means such as an electric motor. The intake pipe 27^a of said pump is projected into the fluid containers or receptacles 28. A preferred embodiment of the pump 27 is of the well-known vacuum pressure type, which, by means of the reversal of the direction of the prime mover of said pump, enables the alternate injection of fluid into said unit containers and the drainage thereof. In this manner said containers may contain the chemical hair treating fluid initially, after which the containers may contain a neutralizing fluid and finally a cleansing fluid is pumped into the tube system to remove and thoroughly cleanse the hair of all residue of previous fluid injections into said containers.

The aforementioned arrangement can comprise separate containers 28 each of which contains one of the fluids mentioned, and which can be connected in rotation with the pipe 27^a in accordance with the manner of treating the hair as already set forth.

The substitution of fluid containers 28 with the pipe 27^a may be effected in any well known manner and does not require a detailed description of the manner of such container substitution; for instance, the bottle 28 supported on a base 28^a can be lowered by withdrawing the base and inserting another bottle, or the pump together with the intake 27^a and the enclosing stopper can be lifted to give access to the bottle and permit another bottle to be substituted, and the intake and pump can then be replaced.

In such cases, as above stated, after the feeding of the liquid into the fluid container units 20 shall have served the purpose intended, the elevated portion of the system may be lowered below the level of the units 20 thereby enabling the draining thereof and placing said units in readiness for further liquid injection therein.

The spindle or mandrel 29 is of the usual type device employed for winding the hair 31 in coiled form. The hair is wound round said mandrel with the securing latch 30 lifted as indicated by said latch in dotted line, after which the latch is snapped inwardly and held against said hair 31 and the central body of said mandrel by a rubber band (not shown); other means well known to the art for holding the latch 30 can be employed. In this manner the hair is securely held in coiled position as shown in Fig. 5.

Referring to Fig. 7. The shell 32 forming a container may be either metal or plastic material, such as Bakelite. The shell 32 is provided with a slotted opening at the periphery of said shell. The opening aforesaid is large enough to permit the insertion of the projection 33^b of the closure member 33 in the position as shown in Fig. 8.

A portion of the hair from the wearer's head 20^a that is intended to be coiled preparatory for permanent waving, is fed through the slot 33^a of the rubber closure member 33, the latter being preferably made of soft rubber. The manner of feeding the hair through said slot 33^a is shown in Fig. 6.

After the hair is fed through the slot 33^a said hair is wound round the mandrel 29, said hair winding bringing the mandrel close to the closure member 33. The mandrel 29 with the hair wound around it is slipped into place as shown in Fig. 7 simultaneously with said slipping on of the

closure member 33, in the manner shown in Fig. 8.

The container 32 is provided with an opening 34 and an end opening 34^a through which the mandrel 29 is thrust within the container 32 aided by the handle 35 attached to said mandrel 29. The soft rubber plug 36 is inserted in the opening 34 at the right end of the container (see Fig. 7), and a liquid tight closure results by reason of said plug which serves to effect the closure. The plug 36 is locked into position by reason of slotted opening 36^a which presses against the projection 33^b of the closure member 33. Said position is necessary to maintain the mandrel 29 with respect to the hair on the head of the wearer.

The tube 21 extends into the mandrel 29, said tube being provided with perforations 21^a as shown in Fig. 9, to permit liquid to penetrate to the other surface of the mandrel. The end of the mandrel 29 through which the tube 21 projects, has a beveled thread 21^c. A screw joint member 37 is screwed over said thread 21^c. Said joint member makes possible a liquid tight closure of the opening 34^a.

A vent pipe and valve arrangement 38 is provided for the container 32, which arrangement provides for the escape of air in the piping system to permit the circulation therein of whatever liquid is injected into said system and, including the coiled hair containers which are a part of said system. A "circulation" means a cyclic flow, and for this purpose a return system to the bottle, such as one duplicating the distribution system, can be connected to the vent pipes 38 of each applicator shown in Fig. 7.

Referring to Fig. 4, there is illustrated a modification of the container shown in Fig. 7. The container 20 is made preferably of flexible rubber in the shape shown in Fig. 4. Other forms of rubber containers can be used.

The container is opened in the manner shown in Fig. 3 and is closed as shown in Fig. 2. The latch 38^a is pivoted at the bearing 39 which is secured to the arm lever 40. Said arm lever moves in the bearing 41 which is attached to the closure bar 42. A pin 43 serves to hold the extension lever arm 44^e which is secured to the opposite closure bar 44^a. Said closure bars 42 and 44^a have a soft rubber covering, 44^b and 44^c respectively, to provide watertight closures when said closure bars 42 and 44^a are closed and locked. The locking of the container is performed by hooking the end of the extension arm 44^e behind the pin 43 and bringing the closure bars 42 and 44^a together after which the arm lever 40 is swung over and the latch 38^a and the hook 44^e are brought into the position as shown in Fig. 2. The slipping of the hook 44^e out of closed position after being locked is prevented by the toothed section of the latch 38^a.

The opening of the container 20 as shown in Fig. 3 exposes a pouch bag interior of sufficient size to hold the spindle 29. The hair to be curled is passed between the closure bars 44^c and 44^b after which the hair is wound round the spindle 29 in the manner shown in Fig. 5. The fluids required for treatment of the hair curl are supplied through the tubing in the manner already described. The tubing 21 is reinforced by rubber reinforcement 21^b. Overlap sections 50 and 50^a overlap the respective soft coverings 44^b and 44^c.

Figs. 12, 13 and 14 show a further modification of the hair curl container, the container 47 proper is made up of two sections 45 and 45^a. The rub-

ber closure member 33 is slipped into the opening 46 provided therefor. The container may be of metal or a plastic like Bakelite with an inner lining of rubber.

The hair to be curled is fed through the opening 33^a of the closure member 33 in the usual manner and afterwards wound round the spindle 29. The spindle is placed in one of the half sections of the container 47, and then the parts 45 and 45^a are joined together by the bent bar 48 being secured under the loop bar 49 at both ends of the container 47 as shown in Fig. 14.

The opposite closure is made by locking the clasp 50, thereby securing said sections together in a liquid tight manner, said container being reinforced by soft rubber circlets at the closure end of the spindle or mandrel 29 as shown in the broken section of Fig. 12. Also the top portion of section 45^a and the bottom portion of section 45 is rubber reinforced as seen in Fig. 14.

A particular feature of my invention resides in the fact that the coiled hair is secured in taut position by means of the mandrel 29 and the latch 30 thereof. The function of the closures of the container units shown in the drawings is for the purpose of maintaining a liquid and air-tight closure medium, the coiled hair within each of said container units being secured in position for cold wave treatment by the mandrel 29 in the manner described.

Particular attention is also directed to the preferred container unit shown in Fig. 4, the outer covering of said unit being made of resilient and flexible material, such as soft rubber, which enables the ready insertion of the mandrel 29 with the coiled hair thereon into said container without the slightest discomfort to the person upon whose head the permanent hair wave is being performed.

It will thus be seen that the arrangement herein shown and described for permanent hair waving enables an operator to accomplish the waving of the hair in a very short period of time and without the slightest discomfort to the person whose hair is being so treated. Moreover, the necessity of heat treatment is entirely eliminated. The maintenance of the liquid away from direct contact with the scalp permits the use of any softening agent without danger; it is preferred, however, to use a water solution of hydrogen sulfide or a non-toxic agent.

In the operation of the device with the simplified form illustrated, the pump is started, after the applicators are in position, to force the liquid from the bottle into the containers. A positive and continuous pressure is thus applied upon the liquid and this is equalized on all the applicators; thereby there is insured a uniform treatment of all the curls. Pressure is maintained for the period required; and thereafter the liquid can be released through the vent pipes 33 and collected in a suitable receptacle or returned to the bottle, or the pump rotation can be reversed to create a suction upon the containers and thus draw the liquid out of the curled strands. The bottle of softening liquid is then replaced by one containing a neutralizing solution and the operation is repeated. Then a cleansing liquid is substituted and the operation repeated to wash and remove all traces of the chemicals. Since the containers are closed during these operations there is no leakage of liquid nor is there escape of gaseous odor to any noticeable degree.

While the invention has been described in detail with specific examples and modifications such examples are illustrative and are not given as limitations, since other modifications within the spirit and scope of the invention will be apparent to those skilled in the art.

Now having described my invention, what I claim is—

1. An apparatus for treating hair upon the head of a person including a container and a mandrel, a portion of said hair being curled or wound upon the mandrel and secured thereon, said mandrel being insertible through an opening in the container and said container having sealing means for rendering said opening air and liquid tight after said mandrel has been inserted therein; tubular liquid conveyor means connected with the inner section of said container, a pump operably connected with said liquid conveyor means to alternately fill and drain said container of fluids acting upon said coiled hair portion thereby causing said hair to be waved in the manner set forth.

2. An apparatus of the class described including a container, said container having closure means thereon whereby said container is made liquid and air tight, said closure means including a slotted opening through which a portion of hair from the head of a person is projected therethrough, a mandrel attachable within said container upon which said hair portion is wound and secured thereon, tubular conveyor means inserted in said container, a pump operably connected with said tubular conveyor means, a liquid storing means connected with said pump through piping means, said pump to cause a liquid flow from said liquid storing means to said container through the medium of said liquid storing means, said pump likewise causing the drainage of said liquid in said container upon the reversal of direction of operation of the pump aforesaid.

3. An apparatus of the class described, including a group of closure containers, said containers attachable to the head of a person whose hair is to be waved, each of said containers having a resilient slotted opening through which a portion of the hair from the head of said person is projected therethrough; a mandrel attachable within each of said containers and upon which said hair portion is wound and secured thereon, locking means for the air and liquid tight closure of each of said containers, said locking means including means for the closure of each of said respective slotted openings; tubular liquid conveyor means attached to each of said containers, liquid supply and drainage means attached to said conveyor means whereby liquids may be alternately conveyed to and drained from the group of containers aforesaid.

4. An apparatus for treating hair upon the head of a person including a series of containers attachable to the head of said person, each of said containers constructed of flexible material, a closure member attachable at the opening of each of said containers, said closure member having a slotted opening through which a portion of the hair to be waved is inserted, a mandrel insertible in each of said containers after said hair portion that has been inserted through said slotted opening of said closure member and wound around said mandrel and secured thereon, locking means on each of said containers to secure and lock said closure members into said

container opening whereby said container is made air and liquid tight; tubular liquid conveyor means attached to each of said containers, liquid supply and drainage means attached to said conveyor means whereby liquids may be alternately conveyed to and drained from the group of containers aforesaid.

5. An apparatus of the class described including a series of containers, each of said containers having a resilient closure member, said closure member having a slotted opening through which a portion of the hair from the head of a person is projected, a mandrel attachable within each of said containers upon which said hair portion is wound, means for the closure of said containers, said closure means including said closure member whereby each of said containers is made air and liquid tight, tubular conveyor means inserted in each of said containers, said tubular conveyor means including liquid storage means and pumping means for alternately conveying liquid supply and the drainage thereof in each of said containers, whereby said hair portion in each of said containers may be treated by the liquids conveyed to said containers and the drainage thereof after said hair treatment shall have been made.

6. The structure as set forth in claim 1, said container including two sections, each of said sections having an inner rubber lining, said sections hinged at each end thereof by a pair of hooked jointures, and hasp locking means at the opposite side of said hinged sections, a closure member of soft rubber material affixed in the opening portion of said container, said closure member having a slot opening through which a portion of the hair is fed and then wound around said mandrel, and secured thereon said closure member affixed in said opening portion of said container after said mandrel is inserted therein, said container being locked and sealed upon said affixing of said closure by the hasp locking means aforesaid.

7. The structure as set forth in claim 1 and a controllable air vent on the wall of said container to permit the escape of air in said tubular liquid conveyor means just prior to the injection of the liquid within the conveyor aforesaid.

8. The structure as set forth in claim 1, said tubular liquid conveyor means including a series of separate tubes, each of said tubes terminating into one of said containers, said tubes joined to a central multiple tube connection, said multiple tube connection connected by piping means to said liquid supply and drainage means aforesaid.

9. The structure as set forth in claim 1, said liquid supply and drainage means including a pump and storage means operably attached thereto, whereby said liquid supply may be conveyed to said containers and afterward drained therefrom through the medium of the alternate action of the pump aforesaid.

10. The structure as set forth in claim 1, said

liquid storage means including two or more liquid receptacles interchangeably connected whereby different liquids may be alternately conveyed through said tubular conveyor means into said containers and followed by the drainage thereof for the purpose set forth.

11. An apparatus for treating hair upon the head of a person including a container and a mandrel, a portion of said hair being curled or wound upon the mandrel and secured thereon, said mandrel being insertible into the container and said container having sealing means thereon whereby said container is made liquid and air tight while said hair portion is contained therein; tubular fluid conveyor means connected with said container, pumping means connected with said tubular conveyor means, fluid storage means connected with said pumping means through the medium of piping means, said pumping means to cause by direct action thereof the injection of a cold chemical fluid from said liquid storage means into said container through the medium of said fluid conveyor means, and said pumping means by reverse action thereof to cause the drainage of said chemical fluid in the container aforesaid.

12. The structure as set forth in claim 11, and valve transferring means in said fluid storage means whereby separate fluids in alternate succession may be injected into said container and the drainage thereof thereby completing the cycle of operations for the waving of said hair portion in the manner set forth.

13. An apparatus for treating hair upon the head of a person including an applicator comprising in combination a mandrel for curling a strand of hair and a container for liquid for enclosing the mandrel, said container having an opening for receiving the strand of hair and having sealing means for the opening for preventing escape of liquid from the container, liquid-conveying means connected to said applicator and opening thereinto, and a pump connected to said conveying means for forcing liquid into said container under a substantially equalized and continuously applied pressure.

14. An apparatus for treating hair upon the head of a person including a plurality of applicators, each of said applicators comprising in combination a mandrel for curling a strand of hair and a container for liquid for enclosing the mandrel, said container having an opening for receiving the strand of hair and having sealing means for the opening for preventing escape of liquid from the container, liquid-conveying means including branch tubes connected to each of the applicators and opening thereinto, and a pump connected to said conveying means for forcing liquid into the applicators whereby pressure on the liquid is substantially equalized among the applicators and continuously applied.

VICTOR LEON.
